UNITED STATES PATENT OFFICE.

MAJOR H. E. BECKLEY, OF CHICAGO, ILLINOIS.

HOLDER FOR MAPS OR THE LIKE.

1,163,310.

Specification of Letters Patent.

Patented Dec. 7, 1915.

Application filed November 9, 1914. Serial No. 870,989.

To all whom it may concern:

Be it known that I, MAJOR H. E. BECKLEY, a citizen of the United States, residing at Chicago, in the county of Cook and State of Illinois, have invented a certain new and useful Improvement in Holders for Maps or the like, of which the following is a full, clear, concise, and exact description, reference being had to the accompanying drawings, forming a part of this specification.

My invention relates to holders for maps or other articles, and especially to a type of holder which will accommodate a plurality of maps or other articles and at the same time permit any desired one of said maps or articles to be withdrawn for inspection and then returned.

The principal object of the invention is to provide a simple, practical and efficient type or construction of holder for maps or the like which shall permit the separate maps or articles to be easily and quickly drawn out of the holder for exhibition and as readily returned, and which will permit any desired map or article to be drawn out into the same position where a previous map or article has been drawn.

Other objects of the invention will appear more fully in connection with the following description.

In the accompanying drawings Figure 1 is a holder for maps or other articles embodying my invention; Fig. 2 is a longitudinal section through the same; and Fig. 3 is a transverse section, showing one of the maps or articles partially withdrawn from the holder.

Referring to the drawings I show a bracket 1 by which the holder proper may be mounted or supported in any convenient place, as for example upon the wall of a room or elsewhere. This bracket 1 is made of suitable shape or form, as for example a main back piece having lateral projections 2-2 at its ends. Between the projections 2-2 is arranged the holder proper 3 which as shown conveniently consists of a long body portion preferably made octagonal in cross section, as shown in Figs. 1 and 3, and having octagonal end pieces 4-4, the intermediate portion being formed by longitudinally extending boards or flat members 5-5. The boards or members 5-5 do not quite touch each other, but are separated by small spaces, or slots, as shown in Fig. 3, through which maps or similar arti-

cles 6-6 may pass. The maps or articles 6-6 are mounted upon rollers 7-7 which are arranged inside of the body 3, being conveniently mounted upon supports 8-8 secured to the several boards or members 5-5. The rollers 7-7 are preferably provided with spring members, (not shown) similar to curtain rollers, whereby said rollers tend normally and continually to roll up the maps or articles 6-6. Said maps or articles 6-6 are, however, provided at their outer ends with end pieces or rods 10-10 of larger width or size than the spaces between the boards or members 5-5 whereby said maps may be rolled upon the rollers 7-7 by the action of the latter, but cannot be drawn entirely within the body 3. Rings 11-11 are conveniently provided upon the rods 10-10 whereby said rings may be engaged by the finger and the map or article withdrawn.

The body 3 is preferably mounted for rotation upon the projections 2-2, whereby said body may be turned as desired to bring any particular map or article into any desired position for withdrawal. The mounting shown conveniently consists of a rod 12 extended centrally through the body 3 and engaging the end members 4-4 thereon and also passing through and engaging inner end members 14 located immediately within the end members 4. The ends of the rod 12 are fitted into sockets in the projections 2-2, the right hand projection 2 (Fig. 2) having an elongated socket 14 by which the end of the rod 12 may be lifted upwardly and out of engagement with said projection 2, to permit the bodily elevation and removal of the member 3 from the bracket 1. Thus the body 3 may be turned one way or the other to permit any desired map or article to be withdrawn, a usual method being to support the entire device in an elevated position and then draw the maps downwardly as shown in Fig. 3. In such case the member 3 may be turned so as to bring any desired map in a downward position and then such a map may be withdrawn and shown or examined, and then permitted to be drawn upwardly and rewound upon its spool or roller 7, by the action of the roller.

It will be understood that changes and modifications may be made without departing from the spirit of the invention.

What I claim is:

1. A device of the class specified having a body or holding member provided with a

plurality of internally arranged spring actuated rollers and constructed with a plurality of longitudinally extending independent members, a member having slots in which 5 said rollers are mounted, provided at each end of said holding member, said slots being closed by said longitudinally extending members, said members being separated from each other to form spaces adjacent said 10 rollers, maps or like articles mounted upon said rollers and passing through said slots or spaces and having their outer ends provided with rods or members, and the adjacent edges of said separated independent members forming stops for said rods or members.

2. A device of the class specified having a body or holding member provided with a plurality of internally arranged spring actuated rollers and constructed with a plurality of longitudinally extending members, a member provided at each end of said strips 20

to which said strips are secured, said members forming a support for each end of said spring actuated rollers, said longitudinally 25 separated members being separated from each other to form spaces adjacent said rollers, maps or like articles mounted upon said rollers and passing through said slots or spaces and having their outer ends provided 30 with rods or members, and the adjacent edges of said separated independent members forming stops for said rods or members, and a member secured to the member to which said strips are secured forming a closure for the ends of the body or holding member.

In witness whereof, I hereunto subscribe my name this 19th day of October, A. D., 1914.

MAJOR H. E. BECKLEY.
